[57] CLAIM

I claim the ornamental design for an RXF-gear, as shown.

DESCRIPTION

FIG. 1 is a front elevational view of the RXF-gear of the present invention;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a rear and right side perspective view thereof; and,
FIG. 8 is a front and right side perspective view thereof
wherein the RXF-gear is rotated in a vertical plane 180°C.
from the view shown in FIG. 7;
